SPliced BAR STRUCTURE

Joseph J. Meyer and Frank A. Jones, Milwaukee, Wis., assignors to G-H Specialty Company, Milwaukee, Wis., a corporation of Wisconsin

Original application March 5, 1941, Serial No. 381,806, now Patent No. 2,318,877, dated May 11, 1943. Divided and this application February 18, 1943, Serial No. 476,344

3 Claims. (Cl. 287—65)

This invention relates to improvements in a spliced bar structure. The present application is a division of our application No. 381,806, filed March 5, 1941, now Patent No. 2,318,877, dated May 11, 1943, and entitled Quilting frames.

It is a primary object of the present invention to provide a novel and simple means by which two bar sections may be provided with a separable scarf joint which will rigidly connect the sections end to end but will be demountable with great facility and erected with equal facility, whereby to be well adapted for use in a knock-down structure.

More specifically, it is an object of the invention to provide an organization in which sockets are provided in each of two scarf joined sections, whereby the pocket of each section receives the end of the other section to complete a joint which is rigid independent of any means positively connecting the respective sections, the connecting means being employed merely to hold the respective sections in the desired interlocking relationship in which such rigidity is assured.

It is a further specific object of the invention to provide a novel and improved type of metal fitting useful in the construction of jointed sections of the type to which the invention primarily relates, such fitting facilitating the manufacture of the jointed sections by being almost instantly applicable to the respective sections for the purpose of readily providing the aforesaid pockets.

Other objects and advantages of the invention will be apparent from the following disclosure thereof.

In the drawing:

Fig. 1 is a view in perspective showing the component parts of a spliced sectional side bar jointed in accordance with this invention.

Fig. 2 is an enlarged fragmentary plan view showing in separated positions the interlocking end portion of the scarf jointed sections shown in Fig. 1.

Fig. 3 is a view taken in section on line 3—3 of Fig. 2.

Fig. 4 is a view in perspective of an open clamp sheath or fitting of the type used in the joint shown in Figs. 1, 2 and 3.

Fig. 5 is a view showing in plan and partially in section an alternate embodiment of the invention.

Like parts are identified by the same reference characters throughout the several views.

The bar illustrated is one which may comprise the side bar of a quilting frame such as is illustrated in the companion application above identi-

fied. Obviously, however, its utility is not limited to this type of construction.

The separable sections 10 and 11 are adapted for end to end coupling by the provision at their respective joining ends 15 and 16 of chamfered portions each terminating at a shoulder 17, as best shown in Fig. 2, to adapt them for complementary engagement to provide a scarf joint.

A sheath fitting 18 is clampingly engaged to each section in a position such that substantially one half of the sheath extends beyond the shoulder 17 over the chamfered portion of the section. The top and bottom walls of each sheath fitting are preferably indented to provide inwardly directed ribs at 19 and 20 which bite into the wood which preferably constitutes the material of the bar sections 10 and 11.

Each sheath fitting 18 is conveniently applied by providing it with serrated end portions 21. When the fittings are clamped to the respective bar sections under pressure, the teeth or serrations at 21 are embedded in the side of the wooden bar as shown in Fig. 3, the ribs 19 and 20 being likewise embedded in the top and bottom walls of the bar. The clamp operation is preferably effected under sufficient pressure to ensure permanent anchorage of the sheath to its respective bar sections. The sheath fitting is originally open as shown in Fig. 4. In its open position it is readily slipped over the bar section to which it is to be applied and the operation of clamping it in place as shown in Fig. 3 is surprisingly quick and simple.

When the sections are joined end to end the respective sheaths 18, in conjunction with the shoulders 17 and the chamfered portions of the respective sections, provide pockets, the extreme end of each section being received into the pocket enclosed by the sheath of the other section. Thereupon the sheaths permit axial movement to and from the above described position of engagement but prohibit all other relative movement between the sections. Consequently it is only necessary to restrain the sections against axial separation to assure their permanent rigidity so long as they remain in assembly.

In the construction shown in Fig. 1 a splicing bar is used at 14 to span the joint between the sections 10 and 11. The bolts 23 perform the dual function of clamping the splicing bar 14 to the bar sections 10 and 11, and also precluding longitudinal separation of the side bar sections 10 and 11. Suitable aligned bores may be provided in the bar sections 10 and 11 and the splicing bar 14 to receive such bolts, wing nuts

24 preferably being used to hold the bolts in their aligned bores subject to quick and easy manual removal to disassociate the bar sections. All lateral and torsional strains are absorbed in the band fittings 18. Therefore splitting of the sections through the bolt bores as the result of rough usage is substantially eliminated.

In the alternative construction shown in Fig. 5, the joint is identical with that described, but instead of using a splicing bar and two bolts, the single bolt 25 is passed directly through the scarf joint to maintain the chamfered ends of the bar sections against longitudinal separation. As before, the only function required of bolt 25 is to preclude longitudinal separation, since the pocketing of the chamfered ends 15 and 16 in the respective fittings 18 absorbs all other strains.

We claim:

1. A sectional bar comprising a plurality of sections adapted for rigid splicing engagement with each other and having complementary end portions chamfered to provide shoulders and beveled extremities extending beyond the shoulders, socket forming bands, one embracing each section adjacent the shoulder and extending beyond the shoulder in partially overlapping relation to the associated beveled extremity, each band having portions permanently connected with its associated section, and other portions extending over the beveled extremities to form sockets into which the beveled extremity of another section may

be fitted, and means for temporarily locking the socketed sections against relative longitudinal movement.

2. A bar formed in detachable sections having 5 mating end portions chamfered to provide shoulders and beveled extremities extending beyond the shoulders, said shouldered portions being provided with bands interlocked with unshouldered portions on a plurality of sides of the 10 respective sections and extending over portions of the beveled extremities to provide sockets into which the beveled extremity of a mating section may be received with a wedging action, and means for temporarily locking the mated sections against longitudinal separating movement.

3. A bar formed in detachable sections having mating end portions chamfered to provide abrupt shoulders and complementary beveled end portions extending beyond the shoulders, each section 20 having its shouldered portion permanently embraced by a wide band having ribs and end portions partially embedded in its associated section, with one side of the band projecting over the shoulder in partially covering relation to the beveled extremity and forming a socket into 25 which the beveled end portion of a mating section may be fitted, and means detachably engageable with both sections for temporarily locking them against relative longitudinal movement.
